[57] CLAIM

The ornamental design for a mowing disk, as shown and described.

DESCRIPTION

FIG. 1 is a top plan view of a mowing disc showing our new design;

FIG. 2 is a bottom perspective view thereof;

FIG. 3 is a top perspective view thereof;

FIG. 4 is a top plan view of a mowing disc showing a second embodiment of our new design;

FIG. 5 is a bottom perspective view of FIG. 4;

FIG. 6 is a top perspective view of FIG. 4;

FIG. 7 is a top plan view of a mowing disc showing a third embodiment of our new design;

FIG. 8 is a bottom perspective view of FIG. 7;

FIG. 9 is a top perspective view of FIG. 7;

FIG. 10 is a top plan view of a mowing disc showing a fourth embodiment of our new design;

FIG. 11 is a bottom perspective view of FIG. 10;

FIG. 12 is a top perspective view of FIG. 10;

FIG. 13 is a top plan view of a mowing disc showing a fifth embodiment of our new design;

FIG. 14 is a bottom perspective view of FIG. 13;

FIG. 15 is a top perspective view of FIG. 13;

FIG. 16 is a top plan view of a mowing disc showing a sixth embodiment of our new design;

FIG. 17 is a bottom perspective view of FIG. 16;

FIG. 18 is a top perspective view of FIG. 16;

FIG. 19 is a top plan view of a mowing disc showing a seventh embodiment of our new design;

FIG. 20 is a bottom perspective view of FIG. 19;

FIG. 21 is a top perspective view of FIG. 19;

FIG. 22 is a top plan view of a mowing disc showing an eighth embodiment of our new design;

FIG. 23 is a bottom perspective view of FIG. 22;

FIG. 24 is a top perspective view of FIG. 22;

FIG. 25 is a top plan view of a mowing disc showing a ninth embodiment of our new design;

FIG. 26 is a bottom perspective view of FIG. 25;

FIG. 27 is a top perspective view of FIG. 25;

FIG. 28 is a top plan view of a mowing disc showing a tenth embodiment of our new design;

FIG. 29 is a bottom perspective view of FIG. 28; and

FIG. 30 is a top perspective view of FIG. 28.
